UNITED STATES PATENT OFFICE

CLINTON L. WALKER, OF PIEDMONT, CALIFORNIA

PISTON

Application filed May 23, 1928. Serial No. 279,953.

This invention relates to pistons and particularly that type employed in internal combustion engines.

In the operation of internal combustion engines of the high speed type, it is desirable to make pistons particularly of the trunk type, as light as possible. The use of aluminum or alloys thereof in piston construction has been extensively attempted and solves the problem of weight reduction. Aluminum, however, has a greater coefficient of expansion than cast iron and as a result considerable clearance must be allowed between the piston and the cylinder wall to allow for the greater expansion of the piston. This leads to poor compression when the engine is cold, leakage of oil and gases, piston slap, etc. Furthermore, aluminum wears exceedingly when highly heated and the clearance or loose fit provided soon becomes too great.

The object of the present invention is to provide a composite piston; that is, a piston consisting of a main body, of an aluminum alloy and an exterior shell constructed of cast iron or steel; to provide a piston which will expand or contract in diameter in harmony with the expansion or contraction of the bore of the cylinder; and further to produce a piston which will have a longer life and offer better friction conditions.

One form which my invention may assume is exemplified in the following description and illustrated in the accompanying drawings, in which:

Fig. 1 is a side elevation of the piston, showing the application of the cast iron shell.

Fig. 2 is a central vertical section of the piston.

Fig. 3 is a cross section on line III-III, Figure 1.

Referring to the drawings in detail, and particularly to Figures 1 and 2, A indicates the head of the piston, B the ring portion, and C the skirt. The ring portion is provided

with the usual grooves 2 for the reception of the piston rings, and the interior of the piston is provided with the usual bosses 3 for the reception of the wrist pin. The skirt portion is in this instance reduced in diameter substantially from end to end for the purpose of receiving a cast iron shell generally indicated at E, and large grooves 7 and 8 are formed at the upper and lower ends of the reduced portion, these grooves being provided with inclined seats as indicated at 9 and 10. The shell proper may be constructed of cast iron or steel and it is made in two or more segments, as indicated at E and F, the line of division between the segments being shown at 4. The upper and lower ends of the shell sections E and F are provided with inwardly turned annularly disposed flanges 11 and 11^a, which engage the seat members 9 and 10, and the exterior surface of the shell sections are grooved as indicated at 12, to receive babbitt rings as the babbitt is poured into the grooves and is afterward machined and finished to the proper diameter.

The purpose of this invention is to construct a composite piston consisting of an aluminum body and an exterior shell, which will maintain a constant degree of contact with the cylinder walls particularly along the skirt portion, when subjected to varying temperatures; and further to produce a piston which will offer better friction conditions. The co-efficient of expansion of aluminum compared with cast iron is 1.9 to 1; that is, aluminum expands nearly twice as much as iron or steel. Hence, if the piston is heated, the gap indicated at L opens up more than the length of the cast iron shell and it is therefore necessary to compensate for this inequality in expansion between the piston skirt and the shell. This is accomplished by providing the inclined annular seats 8 and 9 and the inturned angularly disposed flanges 11 and 11^a; that is, the diameter of the skirt portion always increases when the piston is heated and this increase in diameter com-

penses for the increase in the length of the gap indicated at L. This compensation permits the shell or shoe sections E and F to maintain a constant contact with the inner walls of the cylinder providing the angle of the seats 9 and 10 is correct. This angle is found from the equation that the tangent of the angle

$$10 \quad O = \frac{L(EpTp - EsTs)}{D(EpTp - EcTc)},$$

where L is the length of the shell and Es and Ts its coefficient of expansion and temperature change, Ep and Tp the coefficient of expansion and temperature change of the body or skirt portion of the piston and D its diameter, and Ec and Tc the coefficient of expansion and temperature change of the cylinder wall. The temperature changes in the piston skirt, in the shell and in the cylinder wall would have to be observed under all variations of motor conditions of operation before applying the formulæ, the greatest change being just after starting a cold motor.

15 In actual practice, when designing pistons of this character for a given size or type of motor, the angle O is first determined by calculation, by using the above formula.

20 For the sake of description, it will be assumed that the calculated angle is 38 degrees. In that case a number of pistons will be made, one having an angle of 39 degrees, another 38 degrees, another of 37 degrees, another of 36 degrees, etc. These several pistons will be placed one by one, in the motor and operated under testing conditions. While testing these pistons it may be found that the 39 degree angle has a tendency to seize the moment the motor heats up; the 38 degree angle may also have a tendency to seize; the 37 degree angle may operate satisfactorily under all temperature conditions and loads, and the exact angle suitable for the particular type of motor and piston diameter is thus not only calculated, but practically determined.

25 The following formula may then be developed from the calculated and practical test:

$$30 \quad \tan O = K \frac{L}{D},$$

35 in which K is a variable, determined by experiments, for instance in this case .81 L represents the length of the shell and D the diameter of the piston.

40 It should be realized that as the diameter of the piston increases, new temperature conditions are introduced which may change the variable K, similarly the variable may be changed due to a change in the coefficient of expansion of the particular aluminum alloy employed. It is therefore obvious, whenever a new motor is to be fitted with pistons of this character, that no iron clad rule or formula 45 can be followed, as the angle must first be

theoretically calculated, and finally determined by experimentation.

For a given motor, with a given or known alloy, the variable will become a constant.

50 In the present case, it will be observed that the trunk portion of the piston will heat up more rapidly than the water jacketed cylinder and the piston shell which is in contact with it. The change would undoubtedly be nearly the same in the shell segments and the cylinder wall as the shell segments have contact with the skirt portion of the pistons only at the ends and with the cylinder walls at the rubbing portions of the shell segments. When the angle indicated at O is correctly determined the exterior diameter of the shell sections E and F may be turned to the exact bore of the cylinder with no allowance for expansion as the exterior diameter will remain in constant running contact with the cylinder wall, regardless of contraction or expansion of the aluminum piston skirt. This will produce a quiet running motor. It will reduce piston vibration and weight, the piston will wear longer, and no slap will be encountered when the piston is cold. The babbitt rings indicated at 13 are also important as they maintain the cast iron or steel shell out of actual contact with the cylinder wall and as such will offer better friction conditions, and when wear does occur the babbitt can be renewed without discarding the cast iron shell or the piston proper.

55 It will be observed that the shell is in contact with the piston proper only at the beveled ends and that the shell remains in constant contact with the cylinder wall. Hence, the shell will assume a temperature about the same as the cylinder wall, thereby providing favorable lubricating conditions. A piston of this character can be constructed to be practically as permanent as the remaining parts of the engine. For instance, by leaving extra stock between the ring grooves and extra stock around the wrist pin bosses, wear can be taken up by the use of oversized rings by merely returning the grooves and by reaming the wrist pin holes and inserting oversized wrist pins. The babbitt rings in the shell can be renewed from time to time, thus making it unnecessary to discard the pistons with wear.

60 The babbitt wearing surface offers better friction conditions and hence it is to be expected that the cylinder will wear far less than with the conventional type of piston. This longer wearing life of the cylinder will also be augmented by reason of the elimination of piston slap when the pistons are cold.

65 While certain features of the present invention are more or less specifically illustrated, I wish it understood that various changes in form and proportion may be resorted to within the scope of the appended claims. I similarly wish it understood that

the materials and finish of the several parts employed may be such as the experience and judgment of the manufacturer may dictate or various uses may demand.

5 Having thus described my invention, what I claim and desire to secure by Letters Patent is:

1. A piston comprising a head and a skirt portion, said piston being constructed of an 10 aluminum alloy and said skirt portion having an elongated recess formed therein with angular seats at the upper and lower ends of the recess, and a metallic shell adapted to be received in the recess and having its major 15 surface out of contact with the skirt, said shell having angular faces formed at its opposite ends conforming to the angular seats in the recess and the angle employed being that angle whose tangent is equal to 20 the difference between the longitudinal expansion of the piston portion between the angular seats and the longitudinal expansion of the shell member divided by the diametrical expansion of the skirt member minus 25 the diametrical expansion of a cylinder bore when the piston and cylinder are subjected to operating temperatures.

2. A piston comprising a head, a skirt and a shell member, said skirt member having a 30 longitudinal recess with beveled ends to register with and support inturned beveled ends on the shell member, the angle of the bevels of the skirt and the shell members at each end to a central diametrical transverse 35 plane being such that the trigonometrical tangent of this angle is equal to the longitudinal expansion of the recess in the skirt member minus the longitudinal expansion of the shell member, divided by the diametrical expansion of the skirt member minus 40 the diametrical expansion of the cylinder when the piston is subjected to operating conditions, said shell having its major surface out of contact with the skirt.
